Specification for Design.

Patented Nov. 22, 1921.

Application filed June 24, 1921. Serial No. 480,240. Term of patent 14 years.

To all whom it may concern:

Be it known that I, WILLIAM ROEHL, a citizen of the United States, residing at Manitowoc, in the county of Manitowoc and State of Wisconsin, have invented a new, original, and ornamental Design for a Tackle-Box, of which the following is a specification, reference being had to the accompanying drawing, forming part thereof.

Figure 1 is a perspective view of my improved design.

Fig. 2 is a vertical longitudinal sectional view as indicated by the line 2—2 of Fig. 1.

Fig. 3 is a vertical transverse sectional view on the line 3—3 of Fig. 2.

I claim:

The ornamental design for a tackle box, as shown.

In testimony that I claim the foregoing I have hereunto set my hand at Manitowoc, in the county of Manitowoc and State of Wisconsin.

WM. ROEHL.
